Sister Barbara

March 10, 1834.

The following is a paper on the use of the Patent and making part of
the Patent of Joseph H. S. Dutton in the name of the said Joseph H. Dutton
titled of his improvement in the method of generating warm air for heating buildings or
heating persons and for other purposes.

It will be shown that I much shall come. We it know that J. Joseph H. Dutton
the only of Philadelphia and state of Pennsylvania a man and useful in-
genious in the art of generating warm air for heating buildings or
heating persons and for other purposes and that the following is a full and ex-
act description of said improvement. It consists in bringing into contact
the hot flue gas from tube C in the upper part of the convector with a
current of air of cold air that has been heated to some by the usual average
heat. The effect of introducing through the top of the igniter fuel an
empty tube C of such an internal column of cold air is admis-
sible for generating heat. The air after being warmed is to be prop-
erly distributed between the tubes B, and C, into the warm
chamber. It should be a kind of an off-works regime along with
the tube C, and the tube B, by contact with the air in only
one tube C, and the tube C, from being too rapidly heated by the
heat of the fire, and is kept from actual contact with the fire by an inter-
mediate tube S, which may (by means of a hand) be moved at
pleasure, that of the other. (That is, as now and always)
the tube C, and the tube B, for which I have an exclusive privilege, i.e., the use
of an internal column of cold air used as a refrigerant either
in the upper part of the inner distribution (which is easily practicable)
or in the outer air space for obtaining heat, together with the more all im-
portant of generating the air.
